UNITED STATES PATENT OFFICE

2,532,627

MULTIPLE SWITCH

Jerry C. Koci, Riverside, Ill., assignor, by mesne assignments, to Chicago Coin Machine Co., Chicago, Ill., a corporation of Illinois

Application October 2, 1946, Serial No. 700,756

2 Claims. (Cl. 200—5)

1

This invention relates to an electrical apparatus and particularly to a stepping-relay system. Stepping-relay systems are used in a wide variety of devices, such as in telephone work, signalling systems and scoring systems for various games. The invention provides an improved stepping-relay system wherein one stepping-relay may have a greatly increased range of travel.

A system embodying the invention finds utility in score-indicating means and multiplies the normal range of score indicating systems to any desired expanded range. When incorporated in signalling or communication systems, the stepping-relay system embodying the present invention extends the operation range therefor.

Stepping-relay systems using a ratchet wheel are well known. The angular extent of travel of the ratchet wheel has generally been something less than 360 degrees. Within this angular range, it has been necessary to dispose all the contacts to be controlled over the operating range of the relay. Where a large number of contacts are to be disposed, substantial difficulties arise. Thus, the contact-carrying member becomes large and bulky in order to provide the physical spacing between adjacent contacts angularly disposed around the member. In addition, the ratchet or step-by-step mechanism is generally designed to reduce the angular extent of each step taken by the relay.

By virtue of the invention hereinafter disclosed, it is possible to provide a construction having substantial manufacturing tolerances and free of delicate construction incident to small angular steps. In addition thereto, the construction embodying the present invention may be designed to have an operating range having a substantially greater extent than what has hitherto been considered possible.

In general, the invention provides a construction whereby a ratchet wheel may be stepped in either direction and cooperates with a suitable intermittent movement so that its angular range of operation is extended beyond 360 degrees. In one specific embodiment, the range is increased to almost two complete revolutions. However, modifications may be made whereby additional increments of 360 degrees may be added.

The ratchet wheel cooperates with switching means so that suitable indications corresponding to the position of the ratchet wheel are available.

In order that the invention may be fully understood, an exemplary embodiment thereof is shown in the accompanying drawings wherein;

2

Figure 1 is a top plan view of a relay system embodying the present invention.

Figure 2 is a sectional elevation along line 2—2 of Figure 1 with the relay advanced to an end position.

Figure 3 is a detail similar to Figure 2 but showing the relay system at the normal zero position.

Figure 4 is a view of the contact-carrying portion of the relay and a diagrammatic showing of the circuits in a game control apparatus with which the relay system may be used.

Figure 5 is a modification of the intermittent movement for expanding the operating range of a relay system.

The stepping-relay system comprises base 10 of sheet metal or any other suitable material upon which the entire mechanism is supported. Base 10 has upstanding portion 11 in which is secured rod 12. Rod 12 has part 13 of reduced diameter functioning as a pin. Part 13 at the end thereof has sleeve 14 bolted thereto by means of bolts 15. Sleeve 14 carries insulating member 18 of Bakelite or other rigid insulating material. Insulating member 18 is adapted to carry a series of contacts to be described in detail later.

Cooperating with the contacts on insulating member 18 are wipers 20 and 21, said wipers being carried by supporting member 22. Supporting member 22 has the interior cut out at 23 to provide a generally annular shape. Annular member 22 is rigidly supported in any suitable fashion, such as by arms 25 and 26 extending from ratchet wheel 30. Ratchet wheel 30 has teeth as shown and is rotatable about rod portion 13 and is biased by coil spring 31 having one end rigidly anchored at 32 to ratchet wheel 30 and the other end rigidly anchored at 33 to any suitable stationary member such as insulating disc 18.

Means are provided for returning ratchet wheel 30 back to its normal position and for advancing the ratchet wheel away from a normal position in suitable steps. The ratchet return means include solenoid 36 having armature plunger 37 normally disposed in the position shown in Figure 2 but adapted to be attracted into the interior of the solenoid upon energization of the solenoid winding. Plunger 37 has rod 38 threaded through a suitable aperture therein, which rod links with end 40 of lever 41 pivoted at 42 to plate 11. Lever 41 has end 49 extending through a cut-out in plate 11. Lever 41 has part 43 to which is pivotally secured lever 45. Lever 45 has spring 46 biasing the same, this spring extending between the lever and a suitable pin on plate 11.

Stop 47, having adjusting screws 48, is carried on plate 11 and serves to limit the travel of lever 45 in response to spring 46. Lever 41 has arm 49 extending from portion 43. Pivotaly mounted at 50 on plate 11 is pawl 51 having detent arm 52 disposed adjacent the teeth of ratchet wheel 30. Pawl 51 is biased toward lever 41 by spring 53 disposed between the two.

For advancing the ratchet wheel, solenoid 56 is provided. Solenoid 56 has armature 57 normally in the position shown in the figure but adapted to be attracted within the solenoid when energized. Armature plunger 57 is apertured at 58 and has finger 60 extending therethrough. Finger 60 is carried by arm 62 pivotally mounted upon reduced portion 64 of sleeve 12.

Plunger 57 is biased to the position shown in the drawing by spring 66 extending between a suitable pin on base 10 and the free end of finger 60. Stop pins 67 and 68, carried by plate 11, limit the swing of arm 62 and thus limit the travel of plunger 57. Pivotaly mounted upon arm 62 is pawl 70 having tooth-engaging portion 71 disposed in proximity to the free end of lever 45. A suitable aperture 72 in plate 11 permits end 71 of pawl 70 to pass through from one side to the other of plate 11. Detent 75, pivoted at 76 on plate 11, is also provided, this detent having its free end adapted to engage the teeth of ratchet member 30. Coil spring 77, extending between a pin on plate 11 and an ear on detent 75, biases the detent into tooth-engaging position.

The operation of the relay will now be described. Spring 31 is wound so that wheel 30 will be biased toward some position. In order to return ratchet wheel 30 toward a free unbiased position, this being in a clockwise direction as seen in Figure 2, solenoid 36 must be energized. This causes plunger 37 to move to the left within the solenoid and pull end 40 of lever 41 to the left. Pulling end 40 of lever 41 also increases the tension of pawl 51 on the teeth. However, it will be noted that, in the normal rest position, tooth-engaging part 52 rests on the outermost tip of a tooth. Thus, pawl 51 will permit ratchet wheel 30 to return one tooth clockwise but will catch the same after such advance.

The movement of end 40 of lever 41 to the left results in the movement of end 43 of the lever to the right. This movement pulls lever 45 upwardly and to the right so that the free end thereof is out of the way of the free end of pawl 70. At the same time, arm 49 moves downwardly and pushes detent 75 free of the ratchet teeth.

Detents 51 and 75 are arranged so that one of them always engages the teeth of ratchet 30 so that positive locking will occur.

Upon deenergization of solenoid 36, springs 53 and 77 return the various elements to the position shown in the drawing.

In order to advance the movement of ratchet wheel 30; i. e. to wind up spring 31 more, solenoid 56 must be energized. Upon energization of this solenoid, plunger 57 is moved toward the left. Pawl 70 is thereupon moved along the sloping side of a tooth tip and then beyond to the next tooth, this being in a clockwise direction as seen in Figure 2. By controlling the spacing between stop pins 67 and 68, it is possible to have one movement of plunger 57 move ratchet wheel 30 through an angle corresponding to one, two or more ratchet teeth. Upon the release of the solenoid, spring 66 returns arm 62 to the position shown in the figure, the spring return being suf-

ficiently strong so that pawl 71 engaging a ratchet tooth will cause ratchet wheel 30 to be turned in an anti-clockwise direction as seen in Figure 2.

It is understood that the position of ratchet wheel 30, when the wipers are in a zero position, is such that spring 31 is still wound up. In order to quickly return the ratchet wheel and the contacts back toward this initial position corresponding to a zero contact setting, solenoid 78 having plunger 79 is provided. Plunger 79 is coupled through wire loop 79' to lever 52. Upon the simultaneous energization of solenoid 36 and 78, ratchet wheel 30 will be returned by coil spring 31 to its extreme clockwise position, as seen in Figure 2.

Under normal conditions, the return or clockwise movement of ratchet 30 due to solenoid 36 can only occur after ratchet 30 has been advanced from its normal zero position.

In order to control the angular travel range of ratchet wheel 30, the means shown may be provided. This means comprises lever 80 pivoted at 81 on plate 11. Lever 80 has two prongs 82 and 83 extending generally toward the center of plate 11 and tail piece 84 extending away from plate 11. The pivot is close to prongs 82 and 83. Lever 80 is swingable between two positions determined by stop pins 86 and 87 carried on plate 11 and cooperating with the lever sides. Tail piece 84 cooperates with S-shaped end 90 of movable contact blade 91. Movable contact blade 91 cooperates with relatively fixed contact blade 92, both supported from bracket 93 on plate 11. As will be evident from the drawing, S-shaped end 90 of spring blade 91 tends to move lever 80 to either one of two end positions. Prongs 82 and 83 are adapted to cooperate with pin 96 carried on ratchet wheel 30. Pin 96 is of such a size and so related to the shape of prongs 82 and 83 that a movement of ratchet wheel 30 through one tooth is required to swing lever 80 from one extreme position to the other extreme position.

In the position shown in Figure 2, pin 96 prevents any counter-clockwise movement of ratchet wheel 30. The position shown is the extreme counter-clockwise position of the ratchet wheel. Assuming that ratchet wheel 30 is turned almost 360 degrees in a clockwise direction, pin 96 will thereupon clear left prong 82 and engage right prong 83. Rotation of ratchet wheel 30 will cause lever 80 to be forced over to its other position and maintain the switch closed. On the second turn of ratchet 30 in a clockwise direction, pin 96 will be stopped by prong 82. Thus, ratchet wheel 30 will have a range of 720 degrees less the angle between the two end positions of pin 96. In practice, this angle to be subtracted may be made quite small.

Referring now to Figure 4, a circuit diagram of the electrical connections for a counting system embodying the present invention is shown. Annular disc 22 carries wiper 20 which, at all times, contacts annular ring 100. Disc 22 also carries wiper 21 electrically connected by wire 101 to wiper 20. Wiper 21 is adapted to cooperate with two series of contacts 105 and 106 respectively. Contacts 105 may be used in connection with the lowest numbering steps, such as units in an ordinary decimal system. Thus, as is clearly evident, contacts 105 are spaced at equal angular intervals in groups of nine and are separated from an adjacent series of contacts by spaces 107. Each contact 106 extends over an angular range corresponding to one group of contacts 105 plus one adjacent space 107.

Contacts 105 are connected in a circuit to illuminate or otherwise energize indicating means for showing units one to nine inclusive. Contacts 106 are connected to illuminate or energize indicating means for showing tens. In practice, if a number such as seventeen is to be indicated, the indication corresponding to number ten will merely show a one in the ten place, and the indication for the unit will only show a seven.

As indicated in this figure, disc 18 carries enough contacts so that indications from zero up to and including ninety-nine may be shown. When wiper 21 reaches the position corresponding to one hundred, as shown in the drawing, switch contacts 91 and 92 will be closed, thus closing the circuit for indicating means showing numeral one hundred. Thereafter, wiper 21 may continue to a position corresponding to one hundred ninety-nine.

It is understood that adjacent contacts may be in any desired numerical steps. Thus, in many coin-controlled machines, each movement of wiper 21 from one contact to another may involve a change in scoring of ten, one hundred, or any other number. In such coin-controlled machines, it is necessary to provide means for resetting the scoring means to zero at the beginning of a game. It is also frequently desirable to provide for a free game in the event that the player scores a predetermined amount. The scoring system embodying the present invention may be adapted for such use as shown in the drawing.

Thus, 109 may indicate a suitable coin-controlled means. For simplicity, it is shown as a knob. Coin-controlled means 109 has coin response switch 110 and movable contacts 111 and 112 connected together. Movable contact 111 cooperates with fixed contact 113, while movable contact 112 cooperates with fixed contact 114. The remaining contacts shown for cooperation with movable contact 112 are dead and merely indicate the extent of travel of the movable contacts. As indicated, coin-controlled means 109 is adapted to go from the position shown, which is a normal open position, through a position where movable contact 112 touches contact 114 over toward the extreme right position. Movable contact 111 bears on contact 113 and is maintained in that position for the duration of a game. Suitable timing means may be provided for opening the coin-controlled switches after a predetermined time interval. Inasmuch as coin-controlled switches and means are well known, a detailed description thereof is deemed to be unnecessary.

Contact 113 is connected by wire 116 to leaf 81 and also to contact ring 108. Lamp 109 has leads 118 and 119 going to the winding of relay 120. Relay 120 has movable contact 121 connected by wire 122 to wire 116. Movable contact 121 cooperates with fixed contact 123, this being connected by wire 124 to fixed contact 125 of relay 126. Relay 126 may be inserted in the circuit of one or more of the indicating means. As shown in the figure, relay 126 is in the circuit for indicating sixty. It is evident that relay 126 may be inserted in any other indicating circuit and, in fact, may be inserted in several indicating circuits simultaneously. Thus, relay 126 may be on the ground side of the indicating means for sixty and higher numbers.

Relay 126 has fixed contact 130 connected to the winding of free play relay 131. Relay 131 has movable contact 132 connected to wire 122

and has fixed contact 134 connected to line 135, this being the main energizing line for the entire system. Ground 133 will be the other side of the main energizing system. In practice, 135 and 136 will be in a low voltage, secondary circuit. Line 135 is connected through coin-responsive switch 110 to movable contacts 111 and 112. Contact 114 is connected through solenoids 36 and 78 to ground.

The operation of the system shown in Figure 4 is as follows. Assuming that coin-controlled means 109 is in the position shown, upon the insertion of a coin, switch 110 is closed and means 109 may be turned. During the turning movement, contact 112 will close the circuit to contact 114 through relays 36 and 78. This will release ratchet wheel 30 and permit the same to return in response to the bias of spring 31 to the position shown in Figure 3. This corresponds to the position shown in Figure 4, as far as wiper 21 is concerned, with the exception that contact leads 91 and 92 are open. Further movement of coin-controlled means 109 will move contact 112 to a dead position while keeping contact 111 on contact 113.

Now assume that a game is being played. It will be understood that the game, if requiring motors and other apparatus, will be energized from main lead 116. As scoring values are made, wiper support 22 is rotated in an anti-clockwise position as seen in Figure 3. During the course of the game, it is possible that ratchet wheel 30 may be moved backward in a clockwise direction, as seen in Figure 3, in the event that some scores are lost. Assuming, however, that scoring values are added in sufficient number, wiper 21 will be moved in a clockwise direction, as seen in Figure 4. After one complete turn of ratchet wheel 30, contact leads 91 and 92 will be closed, thus energizing relay 120. If the scoring value is sufficiently high, at least one hundred sixty in the drawing, relay 126 will close. When both relays 120 and 126 are closed, a circuit through relay 131 is established. This circuit short circuits switch 110 and permits of the operation of coin-controlled means 109 without a coin. Thus, upon the end of a game, coin-controlled means 109 may go through its normal cycle without a coin.

In order to apply the invention to a system permitting a larger angular travel of the stepping relay than disclosed in Figures 1 to 4 inclusive, a modified intermittent mechanism, as shown in Figure 5, may be provided. Thus, ratchet wheel 30 is provided with pin 96 as before. However, mutilated pinion 150 pivoted at 151 on member 11 is provided. Mutilated pinion 150 has a number of teeth 152. Cooperating with mutilated pinion 150 is index disc 154 having index steps 155 cooperating with roller 156 carried by spring 157 suitably mounted on plate 11. It is understood that index steps 155 cooperate with teeth 152 so that mutilated pinion 150 may be moved one tooth at a time by pin 96 in a manner generally resembling a Geneva intermittent movement.

Mutilated pinion 150 carries movable switch contact 160 cooperating with a series of fixed contacts 161, 162, 163 and 164. Thus, for each complete turn of ratchet wheel 30, movable contact 160 is moved from zero to contact 161 and then to the remaining contacts. The indicating means will, therefore, advance successively to the highest value possible for the system, in this particular case four hundred ninety-nine.

It is understood that the modification shown in Figure 5 may be applied to Figure 4 so that free games and other features may be provided. In fact, additional means may be provided whereby one free game will result for one score, two free games for a higher score, and additional free games for still higher scores.

What is claimed is:

1. A switching system for counters and the like comprising a stationary disc having a group of contacts mounted along the arc of a circle and being spaced uniformly from each other except between the end contacts, said end contacts being spaced a distance substantially greater than the distance between other adjacent contacts, a 15 rotatable wiper cooperating with said contacts, count-indicating circuits having a common return through said wiper and having individual connections to said contacts so that when a wiper touches a contact a circuit corresponding to a 20 certain count is closed, a switch disposed in proximity to said disc, said switch having relatively movable contacts, circuit means controlled by said switch, said circuit means including count-indicating means, an arm for operating 25

said switch, and means rotatable with said wiper for operating said arm, said means being so oriented with respect to the wiper as to operate said arm and change the condition of said last named switch when the wiper of said group of contacts reaches the space between the end contacts whereby said group of contacts may be made to cover a greater counting range by operation of said last named switch.

2. The system of claim 1 wherein said arm operating means includes a pin.
